DIE STOCK

Tideman M. Lilleberg, Chicago, Ill., assignor to
 The Nye Tool & Machine Works, Chicago, Ill.,
 a corporation of Illinois

Application January 2, 1932, Serial No. 584,511

3 Claims. (Cl. 10—127)

My invention as to one phase thereof relates to centering devices of cutting mechanisms for pipes, rods and the like, and more especially die-stocks, the centering devices being provided for rotatably 5 engaging the work, the end of which is to be cut, as by a thread-cutting die in the case of a die stock, positioned beyond the centering device, and more particularly to centering devices for use in the cutting of work of different diameters and requiring the adjustment of the centering device 10 to the particular size of the work.

One of my objects is to simplify the construction of the centering means and render them more compact and economical of manufacture.

Another object is to provide a construction of 15 adjustable centering device whereby clogging of the parts thereof, with consequent objection, is minimized; and other objects as will be manifest from the following description.

Referring to the accompanying drawings:

Figure 1 is a face view of a die-stock embodying my improvements, the stock being viewed from the side thereof at which the centering means are located.

Figure 2 is a view like Fig. 1 with a portion of 25 the cover removed, this view being taken at the line 2 on Fig. 5 and viewed in the direction of the arrow.

Figure 3 is a view in side elevation of the die-stock.

Figure 4 is a longitudinal sectional view of the die-stock; a pipe to be threaded being shown in position in the die-stock in all of these views; and

Figure 5, an enlarged broken sectional view of 35 a detail of the structure, the section being taken at the line 5 on Fig. 1 and viewed in the direction of the arrow.

In the particular construction shown the hollow body of the die-stock is represented at 7, and is 40 provided, as is customary in practice, with diametrically opposed socket portions 8 into which the ends of handles represented at 9 and by which the die-stock is manipulated to thread the work, such as the pipe shown at 100, are secured.

One face of the body portion 7 at one side of 45 the socket portions 8 is inset as represented and provided at opposite sides of the opening extending through the body portion 7, with ribs 10 and also with lugs 12 of much less height than the ribs 10 and diametrically opposed. The ribs 10 and lugs 12 are so disposed as shown as to form a framing in which to receive, and confine, a thread-cutting die-block represented at 14.

The face of the body portion 7 from which the 55 ribs 10 and lugs 12 extend is also provided with

ribs 15 of less height than the ribs 10 and lugs 12, the outer faces 16 of the ribs 15 being milled to lie in the same plane and at a right angle to the longitudinal axis of the opening extending through the body portion 7, these ribs forming 60 seating surfaces for the die-block 14 and ensuring the positioning of the latter at a right angle to said axis.

Screwing into the body portion 7 at the sockets 8 adjacent the ribs 10 are clamp-screws 17, the 65 heads 18 of which, extend inwardly beyond the ribs 10 and overlap the outer face of the die-block 14 these screws, when screwed tightly, clamping the die-block against the surfaces 16.

Referring now to the centering means they 70 comprise a circular disklike centrally apertured portion 19 at the end of the die-stock opposite that at which the die-block 14 is located, which forms a support for jaws 20 shown as in the form of curved bars pivoted at their outer ends in 75 grouped relation about, and concentrically with, the longitudinal axis of the opening through the body portion 7, to the portion 19, as represented at 21.

The jaws 20 which preferably are of the form 80 shown and extend at their inner ends across said opening to rotatably engage between them the work 100 contain arcuate slots 22 into which the inner ends of screws 23 carried by a rotatable member 24 and grouped concentrically about said 85 axis, extend, whereby upon rotating the member 24 the jaws are simultaneously moved inwardly toward, or outwardly away from, said axis and at the same speed, depending on the direction of rotation of the member 24, the parts described being 90 preferably so proportioned and arranged as shown that the speed of movement of the jaws will be uniform in moving to any position assuming the member 24 is rotated at a uniform speed.

The screws 23 screw into threaded openings 95 in the member 24 and the portions thereof which extend into the slots 22 are preferably unthreaded as shown (Fig. 7).

The member 24 which forms an apertured cover for the jaws is shown as in the form of 100 a centrally apertured disk 25 flatwise opposing the jaws 20 and provided with an annular flange 26 telescoping with the circumferential edge of the disk-portion 19 and having at its circumferential edge rearwardly extending equidistantly spaced lugs 27 provided with inturned portions 27a which lap the rear face of the disk portion 19. 105

The disk portion 19 at its circumferential edge portion is cut away at equidistant intervals as represented at 28 in order that the portions 27a 110

of the lugs 27, in applying the cover 24 to the disk-portion 19, may clear the edge of the portion 19 to permit the cover to be seated, the portions 27^a of the lugs 27, upon rotation of the 5 cover to a position in which these portions are out of registration with the cut-away portions 28, lapping the disk portion 19 and preventing the cover from separating from the body of the stock, a set screw 29 on the cover and screwing against the edge of the disk-portion 19 holding the cover against rotation thereon.

The screws 23 are assembled with the cover to project into the slots 22 after the cover has been interlocked with the disk-portion 19 as stated, 15 the various parts being so proportioned and arranged that when the screws 23 are positioned as stated they will engage the ends of the slots 22 in the rotation of the cover in either direction before the lugs 27 move into registration with the cut away portions 28 and thus danger of accidental separation of the cover from the body of the stock is prevented.

The feature of providing only two spaced apart seats for flatwise engagement with the die block 25 is of advantage inasmuch as the cost of manufacturing the structure, as compared with structures having a continuous seat for the block, is greatly reduced.

The feature of providing the low lugs 12 not only reduces the cost of construction but permits of the conditioning of the retaining means either for assembly or disassembly of the die block with the stock, by slight rotation only of the clamp-screws 17, it being noted that these 30 clamp screws need be retracted in a slight degree only to permit the die-block to be applied to, or removed from, position, the block sliding along the inner edges of the ribs 10.

The disposition of the milled ribs 15 relative to the low lugs 12 as shown and preferred, viz., at 40 angles to the latter and thus in the direction of movement of the die-block in positioning it in the stock is of advantage as thereby the die-block may be slid to position without obstruction to its movement.

The cover 24 serves to protect, to a marked degree, the slots in the jaws against entry of dirt

and the arrangement of the various parts of the centering means as described not only permits the structure to be made economically but renders it compact in a high degree.

While I have illustrated certain embodiments 80 of my invention I do not wish to be understood as intending to limit the invention thereto as the same may be variously modified and altered and the invention embodied in other forms of structure without departing from the spirit of my invention. 85

What I claim as new, and desire to secure by Letters Patent, is:

1. Centering mechanism comprising a body 90 having a disk-like portion containing an aperture, jaws pivoted on said portion, an apertured member at the outer faces of the jaws and rotatable on said disk portion, said member having lugs lapping said disk portion and holding said member on said disk-portion, said disk-portion having 95 cut-away portions permitting of the assembly of said member with said disk-portion, means on said member engaging said jaws for rocking the latter upon rotating said member, and stop means cooperating with said first-named means for preventing rotation of said member to a position in which said lugs register with said cut-away portions. 100

2. Centering mechanism comprising a body 105 having a disk-like portion containing an aperture, jaws pivoted on said portion and containing slots, an apertured member at the outer faces of the jaws and rotatable on said disk portion, said member having lugs lapping said disk portion and holding said member on said disk-portion, said disk-portion having cut-away portions 110 permitting of the assembly of said member with said disk-portion, and pins on said member and extending into said slots. 110

3. Centering mechanism comprising a body 115 portion, jaws pivoted on said portion and containing slots, an imperforate annular member rotatable relative to said body portion and overlying said slots and projections on said rotatable member extending into said slots for rocking said 120 jaws upon rotation of said member.
